UNITED STATES PATENT OFFICE

172,027

REFLECTIVE SAFETY SIGNAL

Gustave A. Huber, New York, N. Y.

Application July 21, 1952, Serial No. 20,699

Term of patent 3½ years

(Cl. D72—1)

To all whom it may concern:

Be it known that I, Gustave A. Huber, a citizen of the United States, residing at New York, in the county of New York, State of New York, have invented a new, original, and ornamental Design for a Reflective Safety Signal, of which the following is a specification, reference being had to the drawing, forming a part thereof.

The drawing is lined to indicate contrasting colors of red fluorescence on a white background.

Fig. 1 is a front elevational view of a reflective safety signal, showing my new design;

Fig. 2 is a side elevational view thereof; and

Fig. 3 is a top plan view.

I claim:

The ornamental design for a reflective safety signal, substantially as shown and described.
